UNITED STATES PATENT OFFICE.

WILLARD T. SEARS, OF HARTFORD, CONNECTICUT.

SHOCK-ABSORBER.

1,147,272.

Specification of Letters Patent. Patented July 20, 1915.

Application filed March 6, 1913. Serial No. 752,277.

To all whom it may concern:

Be it known that I, WILLARD T. SEARS, a citizen of the United States, residing at Hartford, in the county of Hartford and State of Connecticut, have invented certain new and useful Improvements in Shock-Absorbers, of which the following is a specification.

This invention relates to so-called "shock-absorbers" for vehicles one of the primary objects of the invention being to provide an article of this character which is simple in construction and certain and positive in action and by which relative motion of certain members of the vehicle, will be effectually resisted, and thereby prevent excessive and prolonged vibration of one of such members, such as the body.

In the drawings accompanying and forming part of the present specification, I have shown two of the several forms of embodiment of the invention, which to enable those skilled in the art to practice the same, will be set forth fully in the following description. I do not limit myself to this disclosure; I can depart therefrom in several respects within the scope of the invention defined by the claims following said description.

Referring to said drawings: Figure 1 is a rear elevation of a vehicle provided with shock-absorbing means involving my invention, said shock-absorbing means, however, being merely shown diagrammatically or all the parts thereof not appearing. Fig. 2 is a sectional view of the shock-absorber, and portions of the vehicle. Fig. 3 is a detail view in elevation of a turbine member. Fig. 4 is a sectional elevation of another form of the device, the operating means for the gyrostatic member being omitted as is the case with Fig. 1.

Like characters refer to like parts throughout the several views which are on different scales.

My shock-absorber is capable of advantageous use in connection with vehicles of various kinds but is of especial utility when incorporated in those accustomed to travel over highways or "common roads" as they are known in contradistinction to railroads. While it can be embodied in a railroad car there is generally no necessity therefor as ordinarily the rails are sufficiently smooth to insure easy riding.

The invention comprises as to one of its

broader aspects, a gyrostat for resisting relative motion of any two desired elements or members of the vehicle and usually, but not essentially, these two members will be the running gear and the body of the vehicle the gyrostat being preferably interposed between said running gear and body to secure the desired advantage, viz., ease and comfort to the occupants of the car and the practical elimination of jolts and jars to the mechanical parts on said body. While therefore I prefer that the gyrostat, of whatever nature the same may be, tend to prevent motion of the running gear with respect to the body, the best effects are obtained by having the gyrostat resist motion of the running gear both toward and from the body. Any suitable means may be provided for operating the gyrostat. I prefer, however, that the driving device be of such character that the speed of the gyrostat shall be approximately proportional with the speed of the car so that when the latter is moving slowly a corresponding motion of the gyrostat ensues while when the car is driven fast the speed of the gyrostat will be correspondingly accelerated. I may if desired employ the motor which operates the car, to drive the gyrostat. Said motor can be of any suitable type.

With the foregoing general observations I will now specifically refer to Figs. 1, 2 and 3. In the first of these views an automobile is illustrated in rear elevation, and comprises the body 1 and the axle 35 equipped with the customary wheels. Between the axle (constituting part of the running gear of the car) and the body are situated one or more springs of any desirable kind, there being two of such illustrated and denoted by 7.

The gyrostat shown comprises in its make-up a member which has both a rotary and a revoluble movement, the rotation of said member being ordinarily at very high speed in order to maintain the axis of rotation of said member horizontal. I have already stated, however, that this speed of rotation may vary. The wheel 3 answers satisfactorily as such a rotary and revoluble member being as illustrated, integral with the sleeve 5 which projects oppositely therefrom substantially centrally thereof. Said sleeve is loose on the shaft 20 by which the effect of the rapidly rotating wheel is transferred to the running gear of the vehicle in

the organization shown. The shaft 20 is connected to the vehicle body 1 in some suitable manner such for example as will now be set forth. Said shaft at its inner end is provided with a ball or spherical portion 20' fitting a similarly shaped seat in the lower enlarged end of the pin 2 which constitutes a convenient vertical pivot for securing the revoluble motion of the wheel 3. The pivot 10 or pin 2 as shown extends freely through an opening in the lower part of the body 1, for example the floor thereof, the enlarged portion 2' bearing against the underside of the floor, while the cap 14, constituting part 15 of a stuffing box, is threaded onto the upper end of said pin, which as will be understood turns freely in its opening in the floor of said body. Surmounting the pin or pivot 2 is the nozzle 13, the opening 12 of which 20 registers with the passage 15 through the pin or pivot 2, for a purpose that will herein-after appear.

To rotate the gyrostatic wheel 3 any convenient means may be provided. I may 25 utilize, for this purpose, the hydrocarbon motor or engine which propels the car, the exhaust from which is directed ultimately against some driven part connected with said gyrostatic wheel, the turbine disk 19 being shown for this purpose and being 30 rigid, for instance by being made integral, with the sleeve or elongated hub 3'. The vanes or blades of this disk 19 are disposed to receive the exhaust gases from the engine 35 or motor 40 the exhaust pipe 41 of which is connected with the nozzle 12. The exhaust after passing said nozzle, enters the passage 15 and passes from thence into the passage 42 of the shaft 20 escaping from the latter 40 by way of the ports 43 against the blades or vanes of said turbine member 19 to thereby rotate the same at a high speed and to secure the same function with respect to the gyrostatic wheel 3.

The shaft 20 is shown equipped at its outer end with an anti-friction wheel 4 which presents a convenient means of transferring the resisting effect of said shaft, constituting part of the gyrostat, to the running gear of the vehicle, said running gear, for such purpose preferably having superposed surfaces cooperative with said shaft or more properly with said anti-friction wheel 4 thereon. While these surfaces may 55 be of any desirable character the upper and lower walls of the groove or channel 9 in the casing or housing 11 answer satisfactorily in this connection, said antifriction wheel being disposed in said groove or channel and its periphery being contiguous to the bottom and top thereof. This casing 60 incloses the operative parts of the gyrostat and certain of the parts associated therewith.

As will be understood when the vehicle is

in motion the exhaust gases from the engine are caused to impinge against the blades or vanes of the turbine disk 19 to drive said disk and hence the gyrostatic wheel at a very high velocity which tends to maintain 70 the axis of rotation of said wheel 3 practically horizontal so that when there is any motion of the vehicle up or down, this will be resisted by the gyrostat acting through the wheel 4 in the manner set forth, the resistance being sufficient to quickly deaden or dampen excessive vibration of the body 1.

I have shown but one gyrostat between the running gear and the body of the vehicle and at the rear thereof; the same may be 80 situated at any other desired place or there may be several of them suitably positioned, the invention not concerning primarily the location of said gyrostat or the number thereof although one situated at the rear 85 between the axle 35 and the body 1 or their equivalents is highly advantageous.

In Fig. 4 I have shown one of several other forms of the invention. In this construction, the rear axle is designated by 21 and the body of the car by 28. Through the latter extends the pivot 26 which is ordinarily in construction like the pin 2 already described. To the lower enlarged portion 26 of said pivot pin is pivoted the head 25 of the shaft 30, said enlarged portion being forked to receive said head. On the shaft 30 is the gyroscopic wheel 33 which can be held thereon by the collars 32 and 34 and driven exactly similarly to the wheel 3 100 already described. Said shaft 30 between its ends rotates in the block 29 pivoted as at 31 between the branches of a bifurcation at the upper end of the arm or bracket 28, provided with a pendent pivot 22 extending through a substantially central opening in the axle 21, the arm 23 during the action 105 of the gyrostat revolving about the axis of said pin 22 as a center.

It will be clear from the foregoing description that my invention comprises broadly a vehicle having relatively movable members and means for resisting said relative motion variably and in proportion to the speed of the vehicle; that is the greater 110 the speed the greater the resisting effect.

It will be clear that in the organization shown, the gyrostat serves to prevent relative movement of two members of a vehicle in a direction toward and from each other. 115

What I claim is:

1. The combination of the body and the running gear of a vehicle, a gyrostat supported by one of said parts, the other part having a bearing for movably supporting 120 said gyrostat.

2. The combination of the running gear and the body of a vehicle, a gyrostat connected with one of said parts for revoluble and rotary movements, the other part hav- 125

ing a bearing for supporting the gyrostat during its revoluble movement.

3. The combination of the running gear and the body of a vehicle, a gyrostat connected with said body for rotary and revoluble movements, and means on the running gear for supporting said gyrostat during its revoluble movements.

4. The combination of the running gear and the body of a vehicle, a gyrostatic wheel connected with the body for revoluble and rotary movements, the running gear having superposed annular ways and the gyrostat having a wheel rotative therewith to travel against said ways.

5. The combination of the running gear and the body of a vehicle, a gyrostat connected with one of said parts for revoluble and rotary movements, the other part having an annular way for said gyrostat.

6. The combination of a pair of relatively movable elements of a vehicle, a gyrostat for resisting said relative motion, a turbine member rotative with said gyrostat, and means for directing a fluid against said turbine member, to rotate the same and thereby said gyrostat. 25

7. The combination of the body and the running gear of a vehicle, a rotary pivot connected with said body, a shaft connected 30 by a universal joint with said pivot, a gyrostatic wheel supported by said shaft, and means for applying the effect of said gyrostatic wheel to said running gear.

In testimony whereof I affix my signature 35 in presence of two witnesses.

WILLARD T. SEARS.
